US0D1106229S

(12) **United States Design Patent** (10) Patent No.: **US D1,106,229 S**
(45) Date of Patent: ** Dec. 16, 2025

(54) **DISPLAY SCREEN OR PORTION THEREOF WITH GRAPHICAL USER INTERFACE FOR A SEED FURROW**

(71) Applicant: **DEERE & COMPANY**, Moline, IL (US)

(72) Inventors: **Carolyn R. Herman**, La Porte City, IA (US); **Jason C. Mauer**, Wes Des Moines, IA (US)

(73) Assignee: **Deere & Company**, Moline, IL (US)

(**) Term: **15 Years**

(21) Appl. No.: **29/907,322**

(22) Filed: **Jan. 5, 2024**

(51) LOC (15) Cl. **14-04**

(52) U.S. Cl.

USPC **D14/485**

(58) **Field of Classification Search**

CLAIM

The ornamental design for a display screen or portion thereof with graphical user interface for a seed furrow, as shown and described.

DESCRIPTION

The FIGURE is a front view of the display screen or portion thereof with graphical user interface for a seed furrow, showing our new design.

The dot-dash broken lines illustrate the display screen or portion thereof and form no part of the claimed design.

1 Claim, 1 Drawing Sheet
